United States Patent Office

Des. 193,534
Patented Sept. 4, 1962

193,534

COMBINED REFUSE RECEPTACLE AND SUPPORT THEREFOR

Jacob Schmier, 629 N. 29th St., Allentown, Pa.

Filed May 5, 1960, Ser. No. 60,469

Term of patent 14 years

(Cl. D58—17)

FIG. 3

FIG. 1 is a perspective view of a combined refuse receptacle and support therefor showing my new design;

FIG. 2 is a top plan view thereof;

FIG. 3 is a side elevational view thereof.

I claim:

The ornamental design for a combined refuse receptacle and support therefor, substantially as shown.

References Cited in the file of this patent

UNITED STATES PATENTS

2,098,996	Blake et al. -----	Nov. 16, 1937
2,263,956	Russell -----	Nov. 25, 1941
2,620,588	Critser -----	Dec. 9, 1952
2,857,076	Tolbert et al. -----	Oct. 21, 1958